UNITED STATES PATENT OFFICE.

WILLIAM F. C. KARSTEN, OF MILWAUKEE, WISCONSIN.

RAIL-JOINT.

1,212,777.

Specification of Letters Patent. Patented Jan. 16, 1917.

Application filed September 21, 1916. Serial No. 121,456.

To all whom it may concern:

Be it known that I, WILLIAM F. C. KARSTEN, a citizen of the United States, residing at Milwaukee, in the county of Milwaukee and State of Wisconsin, have invented certain new and useful Improvements in Rail-Joints, of which the following is a specification.

This invention has relation to rail joints, and the nature and objects thereof will be readily apparent to those skilled in the art to which it appertains in the light of the following explanation of the accompanying drawings, illustrating what I now believe to be the preferred embodiment, or mechanical expression, of my invention from among other forms and arrangements, within the spirit thereof or the scope of the appended claims.

20 However, an object of the invention is to provide a rail joint for splicing together meeting ends of rails, and embodying means for reinforcing the rails at this point so as to enable them to support without strain the weight of the rolling stock when passing over the joint to which this invention has been applied.

Another object of the invention is to provide a rail joint having the above-named characteristics, and in addition thereto providing means for sustaining the weight of the car wheels when the same are passing over the space between the ends of meeting rails so as to prevent pounding and loosening of the fasteners.

35 In addition to the foregoing, my invention comprehends improvements in the details of construction, and arrangement of parts to be hereinafter more fully described, and particularly pointed out in the appended claims.

In the accompanying drawings in which similar and corresponding parts are designated by the same characters of reference throughout the several views in which they appear:—Figure 1 is a view in side elevation of a rail joint constructed after the manner of my invention and illustrating its application to the ends of meeting rails, and, 45 Fig. 2 is a vertical sectional view taken on the line 2—2 of the preceding figure.

With reference to the drawings, 1 indicates the ends of meeting rails which are

slightly spaced in accordance with the usual practice.

55 My invention comprises what might be termed fish plates disposed at opposite sides of the rails at the point of juncture thereof, the inner and outer fish plates being designated 2 and 3 respectively. Bolts 4 are extended through apertures provided in the fish plates and registering openings in the rail ends to secure the fish plates to the rails. Each fish plate is provided with an integrally formed base engaging portion 5 extending over the upper surface of the base, and longitudinally disposed and normally horizontal struts 6 are disposed beneath each fish plate, and are connected to the base portions 5 adjacent each end thereof by means 60 of integral connections 7. An opening 8 is formed at each side of the rail joint in order that parts therebeneath may be reached.

65 A compressing block 9 is disposed beneath the meeting ends of the rails, one half of the block bearing against each rail end, and a socket 10 is formed in the lower surface of the block. A bolt 11 is provided as a part of this invention, and includes a circular reduced portion 12 at its upper end adapted to be seated in the aforesaid socket 10, the opposite end of the bolt being reduced and threaded as at 13.

70 Both of the struts 6 are substantially uniform in cross section, with their converging sides directed downwardly and toward the vertical center of the rail as indicated in Fig. 2. In this manner, each strut is formed with an inclined upper surface 14 and an 75 inclined lower surface 15, the surfaces being convergent centrally in order to define the peculiar form of configuration as above noted. A wedge block 16 is next provided, and is disposed above and between the struts 6, and is formed with downwardly converging 80 sides 17 which, when the parts are engaged in assembled relation, are against the inclined surfaces 14 of the struts 6. The block is provided with a vertical threaded aperture in which the bolt 11 is in threaded 85 engagement, and a jam nut 18 is engaged upon the bolt above the wedge block to urge the wedge block downward in engagement with the struts 6. A bridge member 19 is 90 next included, and is formed with upwardly extending and diverging extensions 100

95 105 20

adapted to bear against the under surfaces 15 of the struts and is provided with a vertically extending interiorly threaded aperture 21 adapted to receive the reduced 5 threaded end 13 of the bolt 11. A jam nut 22 is then applied to the reduced bolt extension to retain the bridge member in position.

It will be obvious from the foregoing, 10 that if the jam nut 18 is tightened so as to force the wedge block 16 against the edges of the struts 6, an opposing strain in the opposite direction will be directed against the block 9 setting up strain in opposite 15 direction against the under sides of the meeting ends of the rails, and the inner edges of the struts 6. The tendency of the wedge block 16 to spring out the struts 6 may be counter-acted by tightening the 20 bridge member 19 which produces an opposite effect upon the struts. In this manner, the force may be directed downward upon an intermediate portion of the struts so as to produce a tendency to raise the 25 meeting ends of the rails. In this manner, the otherwise unsupported ends of the rails are provided a support inasmuch as, when the wheels of the rolling stock arrive at the juncture of the rails, the downward strain 30 thus produced is counter-acted by the tension bars 6 which resist any downward movement of the rail ends. The extent to which this downward movement of the rails may be prevented, can be regulated by adjusting the wedge block relatively to the bolt in a vertical direction and subsequently 35 effecting an adjustment of the bridge member 19.

The effectiveness of this form of rail 40 joint may be considerably enhanced by providing a laterally extending lug 23 upon the upper portion of the inside fish plate 2 at an intermediate portion thereof so as to be disposed exactly at the meeting ends 45 of the rails. In this manner, the flange of the car wheels in passing over the joint, is temporarily supported upon the lug 23 so as to permit the tread of the wheel to pass over the space between the rail ends without 50 producing the pounding as evidenced in present rail joints wherein no such provision is made.

Thus it will be seen that I have provided 55 a novel form of rail joint, which in addition to forming a means for splicing together the ends of meeting rails, also reinforces the rails at a point where most needed. The device also, with modifications 60 may be adapted to use in connection with switch-frogs, switch blades or the like, or any portion of a railway rail constructed to relieve the strain and having no other support than the inherent resistance of the rails to flexion.

65 While I have illustrated and described

my invention with some degree of particularity, I realize that in practice various alterations thereof may be made, and I therefore reserve the right and privilege of changing the form of the details of construction or otherwise altering the arrangement of the correlated parts without departing from the spirit of the invention, or the scope of the appended claims.

Having thus described my invention, what 75 I claim as new and desire to secure by Letters Patent is:—

1. In a rail joint, fish plates disposable at opposite sides of the rails, a strut beneath the rails at the point of juncture thereof, co-acting members adjustable vertically upon the strut, and tensional members having their intermediate portions engaged between the co-acting members and their opposite ends formed integral with the fish 85 plates.

2. In a rail joint, fish plates disposable at opposite sides of the rails, a depending strut located at the juncture of the rails, said strut being exteriorly threaded, co-acting 90 members mounted on the strut for vertical movement, means for retaining the members in position subsequent to adjustment, and tensional members having their intermediate portions engaged between the adjustable 95 members and their opposite sides formed integral with the fish plates.

3. In a rail joint, fish plates disposable at opposite sides of the rails, a compression block located beneath the rails at the point 100 of juncture thereof, a threaded strut having its upper end seated in the compressing block, a wedge block mounted on the strut for vertical movement, a jam nut mounted on the strut adapted to engage the wedge 105 block to retain the same in position subsequent to adjustment, a bridge member mounted on the strut beneath the wedge block, for co-action therewith, and tensional members having their intermediate portions 110 engageable between the wedge block and bridge member and opposite ends formed integral with the fish plates.

4. In a rail joint, fish plates disposable at opposite sides of the rails, a compression block located beneath the rails at the point of juncture thereof, a vertical exteriorly threaded strut having its upper end engaged against the compression block, tensional members having their intermediate 120 portions disposed at opposite sides of the strut and their opposite ends formed integral with the fish plates, a wedge block mounted on the strut for vertical adjustment and adapted to engage the upper sides 125 of the tensional members, a jam nut on the strut engaging the wedge block to force the same downward thereby urging the intermediate portions of the tensional members downward to place the same under strain, a 130

bridge member mounted on the strut for vertical movement and beneath the wedge block, to engage the tensional members to prevent spreading thereof, and a jam nut 5 mounted on the strut adapted to engage the bridge member to retain the same in position subsequent to adjustment.

In testimony whereof I affix my signature in presence of two witnesses.

WILLIAM F. C. KARSTEN.
